[57] **CLAIM**

The ornamental design for a handle for a plumbing fitting, as shown and described.

DESCRIPTION

FIG. 1 is a frontal, top perspective view of a handle for a plumbing fitting embodying our new design;

FIG. 2 is a top plan view thereof;

FIG. 3 is a bottom plan view thereof;

FIG. 4 is a front elevational view thereof, the rear, left side and right side elevational views being the same as the front elevational view; and,

FIG. 5 is a cross-sectional view taken along line 5—5 of FIG. 2.
